UNITED STATES PATENT OFFICE.

FREEBORN F. RAYMOND, 2D, OF NEWTON, MASSACHUSETTS, ASSIGNOR, BY MESNE ASSIGNMENTS, TO UNITED SHOE MACHINERY COMPANY, A CORPORATION OF NEW JERSEY.

HEEL-ATTACHING MACHINE.

1,009,710.

Specification of Letters Patent. Patented Nov. 21, 1911.

Application filed February 20, 1892. Serial No. 422,320.

To all whom it may concern:

Be it known that I, FREEBORN F. RAYMOND, 2d, a citizen of the United States, residing at Newton, in the county of Middlesex and Commonwealth of Massachusetts, and whose post-office address is 35 Court street, Boston, Massachusetts, have invented a new and useful Improvement in Heel-Attaching Machines, of which the following is a full, clear, and exact description, reference being had to the accompanying drawings, forming a part of this specification, in explaining its nature.

The invention relates to a heel-attaching machine of the organization hereinafter specified.

Referring to the drawings:—Figure 1 is a view in front elevation of a machine having the features of my invention; Fig. 2 is a view in side elevation thereof; Fig. 3 is a view in vertical section upon the dotted line of Fig. 1; Fig. 4 is a view in plan, and Fig. 5 in section, of the toplift holder; Fig. 6 is a view in elevation of the upper part of the machine showing the jacks and rotary heads facing the same way; Fig. 7 is a view in section upon, and in plan below, the dotted line of Fig. 6; Fig. 8 is an elevation of the upper portion of the machine showing it as provided with a single rotary head and jack; Fig. 9 is a view of a heel-blank with protruding attaching nails; Fig. 10 is a view showing the heel-blank held by its protruding nails to the templet or heel carrier; and Fig. 11 is an enlarged view of the toplift carrier and spanker shown in Figs. 4 and 5.

A is the frame of the machine. It comprises the two uprights a a' , the cross table a^2 preferably integral with the uprights, and it has the two fronts a^3 a^4 .

B is a shaft which is mounted in slide boxes b' b' , which slide in the guides b^2 b^3 , respectively attached to or formed upon the upper end of the sides a a' of the frame. The shaft extends through these boxes and is encircled by the connecting rods C C' which connect the shaft with the cranks c c' respectively of the crank shaft c^2 . At one end of the shaft B is a disk b^4 which carries cam rolls b^5 (see Figs. 1 and 2), and these cam rolls are arranged to alternately travel along the cam grooves in the stationary cam plate b^6 . The cam plate has the switches and in all respects is like the cam plate

illustrated and described in my United States Patents No. 694,665, dated March 4, 1902, and No. 570,648, dated November 3, 1896, and need not further be described here. The shaft B is represented in Figs. 1 and 3 as having the two heads D D'. Each of these heads is shown as provided with four arms d d' d^2 d^3 ; the arms d d^2 each having a yielding perforated templet d^4 adapted to carry a heel-blank into attaching position and drivers d^5 similar to those described in my said United States Patent No. 694,665, dated March 4, 1902; the arms d' d^3 have spanker blocks d^6 and toplift holders d^7 adapted to carry the toplifts into attaching position. I may use, however, heads having one templet only or any desired number of templets, or any desired number of arms with alternating templets and toplift spankers and holders. The bed a^2 supports the two jacks E E', one faces to one front of the machine and one to the other. The jack E is arranged in operative relation to the head D and the jack E' in operative relation to the head D'. Each jack comprises a spindle e , a last or work support e' mounted thereon, and a sleeve e^2 for supporting the spindle extending upward from a base plate e^3 which is shown as having lateral flanges to slide in grooves or ways formed in guide plates supported upon the bed a^2 , in order to permit each jack to be moved into heel-attaching position prior to the operations of attaching a heel and toplift to the shoe, and to be moved out of such position thereafter to facilitate the removal of such shoe from the jack and the application of another shoe thereto. Under each spindle in the bed a^2 is a hole e^4 . In this hole at the bottom is a block of rubber e^5 . Upon this block rests a metal block e^6 with an upward extended threaded spindle e^7 , and upon this threaded spindle e^7 there is fitted an adjustable head e^8 , upon which the jack spindle rests. The shaft e^2 has a gear f which rotates therewith and which is engaged by the pinion f' fast upon the pulley shaft f^2 . Upon one side of the gear f is a member f^3 of a clutch, the other member f^4 of the clutch is arranged to slide upon a key or feather upon the shaft e^2 , and is moved into engagement with the clutch by means of the lever f^5 and spring f^6 ; it is moved out of engagement with the clutch by means of the cam projection f^7

upon the gear f^8 , and the latch f^9 pivoted to the lever f^5 . The latch is connected by a rod f^{10} with the treadle f^{11} . The gear f^8 is free to turn on the shaft f^2 , and is rotated by means of a gear f^{12} upon the crank shaft c^2 , which is keyed or pinned thereon.

A desirable feature of the invention consists in the provision in a duplex machine of two heads or two sets of nailing devices adapted to conjointly operate, and which are arranged upon the same center or practically the same central line of the application of power to them; the center line in this case is the center of the shaft B. Another advantage arises from the location of the heads in relation to each other whereby the templets or heel-blank carriers and toplift holders or carriers are open and exposed and within easy reach of each operator, so that an operator standing in front of his jack may easily place the heels and toplifts in position upon the arms of the head which he is using, or if a boy or assistant is employed to place the heels and toplifts, then he may do so by standing upon the side of the machine opposite that of the respective operator, where he is in a very favorable position to easily and rapidly place them, and this advantage is the same of course whether one or two heads be employed. Of course instead of two heads D D', one of sufficient width to carry two sets of nailing devices may be used. I would say that I do not confine myself to the special manner of turning the shaft B herein described; although I prefer that it be turned automatically.

Of course it is not necessary that the jacks be arranged as shown in Figs. 1, 2 and 3, as they may both face either front of the machine, in which event the operator or operators would stand at one front of the machine, and the attendant or attendants at the other; in other words, the shoes would be handled on one side of the machine only, and the heels and toplifts when placed by attendants would be placed upon the other side of the machine, and in Figs. 6 and 7 I have represented this construction. I prefer, however, to build the machine with two fronts, as shown in Fig. 1, for in this case the machine may be made very narrow, the jacks being quite close together. Where the jacks both point the same way and the machine has but one front it must, of course, be wide enough to allow two attendants to stand side by side, one for each jack.

It will be observed that the boxes b' which bear or support the rotary shaft B, are represented in Fig. 1 as connected with each other by the section B', that is, the two boxes and the section B' constitute a cross-head, while it is not necessary that the boxes be so connected, as the shaft B will in many instances be a sufficient connection.

It is desirable that the machine stop with the rotary heads in their highest or very nearly highest position, and to prevent their falling from this position after the disengagement of the clutch I apply a brake G to the shaft c^2 . It is represented in Figs. 1 and 3 as consisting of a curved bar g pivoted at g' , and having its under surface lined with raw hide or other similar material and drawn forcibly against the hub g^2 of the gear f^{12} by the spring g^3 (see Fig. 3), said spring being attached at one end to the bar g and at its other end to a stationary part of the machine. The toplift holder or carrier is represented in Figs. 4, 5 and 11, and comprises a spanker block having secured to the rear ends of its spanking face the V-shaped gage h by screws h' , the gage h preferably having elongated slots h^2 through which the screws pass and by which it is made adjustable transversely of the block d^6 . The block also has upon its face the yielding breast gage h^3 , which preferably has the straight edge h^4 and against which the breast of the toplift bears. This breast gage h^3 is preferably made as an angle piece with the section h^5 which extends in front of the block d^6 , and is movable with the section h^3 lengthwise of the block, being secured to the block by a sleeve h^6 which enters a hole h^7 in the block, and through which a spring h^8 extends, said spring being connected at one end to the front end of the sleeve and at its other end to the rear end of the block d^6 , thereby acting to draw the breast gage continuously toward the rear gage.

It will be observed that each templet d^4 , which comprises a heel carrying device, is adapted to receive a heel in one position, to carry it into attaching position and to hold it in attaching position while the drivers d^5 are operating to attach the heel-blank to the shoe. It will also be observed that each toplift spanking device or carrier is adapted to receive a toplift out of spanking or attaching position and to carry it into spanking or attaching position and there attach it to the previously-attached heel. During the movement of the carrier the top lift, which has been inserted by an attendant, will be securely held in place by the spring actuated clamping device above described and shown in Fig. 11. It will also be seen that the movements of the heel carrying and attaching device and of the toplift carrying and spanking device are in a vertical plane extending lengthwise of the shoe from heel to toe and that this brings the faces of the heel carrying and attaching device and of the toplift carrying and spanking device into a position confronting the operator or his attendant, so that he may see whether the heel-blank or toplift has been properly placed in its carrying device, and if it has

been improperly placed he can then rearrange it. Not only this but the heel-blank carrying device and the toplift carrying and spanking device, being movable into and out 5 of position lengthwise of the shoe rather than crosswise it, present and hold the heel-blank and toplift in an accurate position in relation to the heel-seat of the shoe, that is, they are in longitudinal alinement with the 10 part of the shoe to which they are to be attached, and any slight imperfection in construction does not operate to throw the heel or toplift out of line with the shoe as it does where the heel-blank carrying and attaching 15 device and the toplift carrying and spanking device are moved in a vertical plane transverse to the length of the shoe. When said devices are moved transversely to the length of the shoe any slight variation in the lateral 20 position of the heel and toplift, and especially the latter, causes unsatisfactory work. It will also be seen that each jack is supported for sliding movements into and out of heel and top-lift attaching position in a line 25 parallel with the vertical plane in which the carrier moves. One advantage following from this arrangement is that it permits adjustment of the jack for accurately positioning the shoe beneath a heel or top-lift sus- 30 tained by the carrier above the shoe, prior to the attaching operation, in the event that the carrier is not moved into the precise position required. It will further be seen that where a single nailing head, such as is 35 shown in Fig. 8, is used, the reciprocating cross-head upon which it is mounted may be made very narrow and that the frame of the machine carrying the jack or work support may also be made very narrow. This 40 is of marked value in the construction of heel-attaching machines because it permits a very strong cross-head of relatively light weight to be employed, and it also enables a stronger but lighter frame to be used and 45 less factory floor space to be required for the machine, thus obtaining a better machine because a stronger machine, a cheaper machine because a lighter one, a more desirable factory machine because more compact and 50 having a smaller base, and a more powerful machine because less power is required for moving the lighter though stronger cross-head.

The form of heel which the machine 55 shown herein is best adapted to attach to a shoe is known as a loaded heel, that is, it is a heel in which the nails are partially inserted or driven. Such a heel detached is represented in Fig. 9.

60 The templet d^4 which carries the heel-blank into attaching position is provided with perforations corresponding substantially to the positions the nails occupy in the heel-blank, so that to apply the heel-blank 65 to the templet, the operator simply places

the heel on the templet with the nails in the heel protruding into the perforations in the templet. The perforations in the templet are slightly larger than the nails, as shown in Fig. 10, so that some of the nails will 70 bind against the sides of some of the perforations in the templet, whereby the heel-blank is frictionally held to the templet or carrier as it is moved from receiving into attaching position and is so held until the 75 nails have been driven from the holes of the templet by the drivers d^5 in the act of attaching the heel to the sole of a boot or shoe. The templet thus serves as a heel-holding and carrying device.

80 The top lift holder, *per se*, is not claimed herein but forms the subject-matter of divisional application Serial No. 572,487, filed July 18, 1910.

Having described my invention, what I 85 claim as new and desire to secure by Letters Patent of the United States, is:—

1. In a heel-nailing machine, in combination with a supporting bed having a plurality of jacks arranged side by side and adapted to support lasts, a reciprocating frame, a rotary shaft mounted therein, its axis being at right angles to the length of the lasts carried by said jacks, and nailing heads carried by said shaft and located over the heel 95 portions of the lasts.

2. In a heel-nailing machine, a supporting bed carrying two jacks, a last carried by each jack, the toes of said lasts pointing in opposite directions and the heels of said lasts being located side by side, a reciprocating cross-head and means whereby it is reciprocated toward and from said jacks, a single rotary cross-shaft mounted in said cross-head over the heels of said lasts and at right angles to the length of said lasts, and two nailing mechanisms located side by side upon said shaft, one over each of said jacks, and adapted to turn on said shaft from rear to front, all as and for the purposes set 110 forth.

3. In a heel-attaching machine, a last or work support, and heel-blank carrying and attaching devices movable upon a vertical arc lengthwise the last or work support from receiving to attaching position, as and for the purposes set forth.

4. In a heel-attaching machine, the combination of a last or work support, heel-blank carrying and attaching devices, and toplift carrying and spanking devices movable upon a vertical arc lengthwise the last or work support from receiving to attaching positions.

5. The combination of the last or work 125 support, the heel-blank carrying and attaching devices, and the toplift carrier and spanker movable upon a vertical arc lengthwise the last or work support from receiving to attaching position, and also vertically 130

movable with respect to the last or work support.

6. In a heel attaching machine, a last or work support, a heel blank carrying and attaching device movable upon a vertical arc lengthwise the last or work support from receiving to attaching position, and means for automatically so moving the said device after the machine has been set in operation.

10 7. In a heel attaching machine, the combination of a last or work support, a heel blank carrying and attaching device, a top-lift carrying and spanking device movable upon a vertical arc lengthwise the last or 15 work support from receiving to attaching position, and means for automatically so moving them after the starting of the machine.

8. In a heel-attaching machine, the combination of a last or work-support, a rotary head constructed to be reciprocated in line with said last or work-support and arranged with its axis transverse to said last or work-support, and devices arranged at intervals 25 circumferentially of said head for sustaining a heel and a toplift in line with the heel end of the last or work-support.

9. A heel-attaching machine, having in combination, means for sustaining a shoe 30 with its sole substantially horizontal, a rotary carrier for sustaining a heel to be attached to the shoe arranged for movement in a vertical arc longitudinally of the shoe from receiving to attaching position, the 35 point about which said arc is described being above the heel when in attaching position, and automatic nailing mechanism for attaching the heel to the shoe.

10. A heel nailing machine, having in combination, a plurality of work supports arranged side by side in position to sustain shoes with their heels in transverse alignment, a plurality of oppositely disposed nailing devices arranged respectively in 45 alignment with said supports, and means for moving relatively said supports and nailing devices to press said heels upon their heel seats and secure them by attaching nails.

11. A heel nailing machine having, in combination, a plurality of work supports arranged side by side in position to sustain shoes, a nailing device disposed oppositely with respect to each of said work supports and in alignment therewith, actuating means 55 for relatively and simultaneously moving said supports and nailing devices to secure heels to shoes sustained by said work supports, and a single controlling device for said actuating means.

60 12. In a heel attaching machine, a shoe support arranged for movement into and out of attaching position, and a carrier for sustaining a heel to be attached to a shoe arranged for movement in a vertical arc, the 65 path of movement of said carrier and said

shoe support being in substantially the same vertical plane, and means for moving relatively said shoe support and said carrier to press the heel upon the shoe.

13. In a heel attaching machine, a shoe 70 support arranged for movement into and out of attaching position, and a top-lift carrying and spanking device arranged for movement in a vertical path from a position behind the shoe support into position over 75 it, the path of movement of said carrier and shoe support being in substantially the same vertical plane, and means for moving relatively said shoe support and said carrier to spank a top-lift on the heel of a shoe.

80 14. In a heel attaching machine, the combination with a work support for presenting a shoe in position for heel attaching and top lift spanking operations, of a nail templet, a gang of drivers mounted with their 85 ends extending at all times into said templet, said templet and said drivers being movable toward and away from the work support to attach a heel to a shoe on said support, together with a top lift carrying and spanking mechanism sustained for movement in a vertical plane extending substantially in the direction of the length of the shoe from top lift receiving position 90 into position to spank a top lift on the heel, 95 and means for moving said mechanism toward the work support to attach the top lift.

15. In a heel attaching machine, the combination with a work support for presenting a shoe in position for heel attaching and top lift spanking operations, of a cross head 100 movable toward and away from said support, a nail templet carried by said cross head and provided with driver passages, 105 drivers arranged for movement relative to said templet, means for moving said cross head and templet toward the work support, said drivers being thereafter movable relatively to the templet to drive heel attaching nails, a top lift carrying and spanking mechanism sustained for movement from the rear in a vertical plane extending longitudinally of the shoe, and means for moving said mechanism toward the work support to attach the top lift.

115 16. In a heel attaching machine, the combination with a work support for presenting a shoe in position for heel attaching and top lift spanking operations, of a movable head, 120 a nail templet and a driver-carrying block supported by said head, a gang of drivers mounted on said block, said templet and said drivers being movable toward and away from the work support to attach a heel to a shoe on said support, a top lift carrying and spanking mechanism sustained for movement in a vertical plane extending substantially in the direction of the length of the shoe from top lift receiving position 125 130

into position to spank a top lift on the heel, and means for alternately moving said templet and said top lift mechanism toward the work support.

5 17. In a heel attaching machine, the combination with a work support for presenting a shoe in position for heel attaching and top lift spanking operations, of a cross head movable toward and away from said support, a nail templet carried by said cross head and provided with driver passages, said templet being constructed to receive and hold a loaded heel, drivers arranged for movement relatively to said templet,

10 15 means for moving said cross head and templet toward the work support to press the heel on the shoe, said drivers being thereafter movable relatively to the templet to attach the heel to the shoe, a top lift carrying and spanking mechanism sustained for movement in a vertical plane in alinement with the shoe from a position at the rear of the machine into position over the shoe, and means for moving said mechanism toward 20 the work support to attach the top lift.

25 18. In a heel attaching machine, the combination with a work support for presenting a shoe in position for heel attaching and top lift spanking operations, of a cross head movable toward and away from said support, a nail templet carried by said cross head and provided with driver passages, drivers arranged for movement relatively to said templet, means for moving said cross 30 head and templet toward the work support, said drivers being thereafter movable relatively to the templet to drive heel attaching nails, a top lift carrying and spanking mechanism pivoted on said head for movement in 35 a vertical arc in alinement with and lengthwise of the shoe from a position behind the heel end of the shoe into position over the heel, and means for moving said mechanism toward the work support to attach the top lift.

40 45 19. In a heel attaching machine, the combination with a work support arranged for movement from position to receive a shoe into position to present a shoe for heel attaching and top lift spanking operations, of a cross head movable toward and away from said support, a nail templet carried by said cross head and provided with driver passages, drivers arranged for movement 50 relatively to said templet, means for moving said cross head and templet toward the work support, said drivers being thereafter movable relatively to the templet to drive heel attaching nails, a top lift carrying and spanking mechanism 55 supported for movement in a vertical arc in alinement with and lengthwise of the shoe 60 from a position behind the heel end of the shoe into position over the heel, and means for relatively moving said mechanism and the work support to attach the top lift.

65 top lift.

20. In a heel attaching machine, the combination with a work support for presenting a shoe in position for heel attaching and top lift spanking operations, of a top lift carrying and spanking device sustained for movement in a vertical plane extending substantially in the direction of the length of the shoe from a position behind the shoe in which the face of said device is substantially vertical into position over the shoe 70 with the face of said device substantially horizontal, and means for relatively moving said device and the work support to attach the top lift.

21. In a heel attaching machine, the combination with a work support for presenting a shoe in position for heel attaching and top lift spanking operations, of a cross head movable toward and away from said support, a nail templet carried by said cross head and provided with driver passages, drivers arranged for movement relatively to said templet, means for moving said cross head and templet toward the work support, said drivers being thereafter movable relatively to the templet to drive heel attaching nails, a top lift carrying and spanking device sustained for movement in a vertical plane extending longitudinally of the shoe from a position in which the face of said 95 device is substantially vertical into a horizontal position above the shoe, and means for moving said mechanism toward the work support to attach the top lift.

22. In a heel attaching machine the combination with a work support for presenting a shoe in position for heel attaching and top lift spanking operations, of a heel blank carrying and attaching mechanism, means for moving said mechanism toward and away from said work support, a top lift carrying and spanking device movable in a vertical arc extending lengthwise of the shoe on said work support from receiving to attaching position, and means for moving 100 said device toward and away from said work support.

23. In a heel attaching machine, the combination with a work support for presenting a shoe in position for heel attaching and top lift spanking operations, of a nail templet provided with driver passages, drivers arranged for movement relatively to said templet, means for relatively moving said templet and the work support, said drivers being thereafter movable relatively to the templet to drive heel attaching nails, a top lift carrying and spanking mechanism supported for movement in a vertical arc 115 in alinement with and lengthwise of the shoe 120 from a position behind the heel end of the shoe into position over the heel, and means for relatively moving said mechanism and the work support to attach the top lift.

24. In a heel attaching machine, a work 130

support for presenting a shoe in position for heel attaching and top lift spanking operations, a blank carrier mounted to swing in a vertical plane about an axis above said work support, automatic mechanism for moving said carrier from a substantially vertical position at the rear of its axis to a horizontal position between its

axis and a shoe on the work support, and means for attaching the blank while held in the latter position.
